UNITED STATES PATENT OFFICE

167,418

JEWELRY COMPONENT

Frederick J. Nielsen, Redmond, Wash.

Application April 14, 1952, Serial No. 19,310

Term of patent 14 years

(Cl. D45—1)

To all whom it may concern:

Be it known that Frederick J. Nielsen, a citizen of the United States, residing at Rt. #2, Redmond, Washington, has invented a new, original, and ornamental Design for a Jewelry Component, of which the following is a specification, reference being had to the accompanying drawing, forming a part thereof, in which

Figure 1 is a top plan view of a jewelry component, showing my new design, and

Figure 2 is a sectional view thereof taken along the lines 2—2 of Figure 1.

I claim:

The ornamental design for a jewelry component, as shown.

FREDERICK J. NIELSEN.
